PAPERBOARD DRUM

Raymond H. Van Saun, Mount Prospect, Ill., assignor to Container Corporation of America, Chicago, Ill., a corporation of Delaware

Application August 21, 1943, Serial No. 499,540

15 Claims. (Cl. 229—5.5)

The present invention relates to paperboard drums and more particularly to a drum construction adapted for the storage and transportation of waxes, asphalt, resins and like materials which are best packaged in hot liquid condition.

Among the objects of the present invention are to provide a paperboard drum of a simple, sturdy form which can be manufactured from ordinary paperboard sheets and which will withstand a large amount of hard usage in storage and transportation.

Other and more specific objects of the invention will become apparent as the description proceeds.

In the drawings:

Fig. 1 is a front view of an assembled drum made in accordance with the present invention, showing a considerable portion of the drum broken away to reveal a fragmentary vertical section;

Fig. 2 is a plan view of the body blank on a somewhat reduced scale from that indicated in Fig. 1;

Fig. 3 is a plan view of a strip of sheet material which is adapted to form a band for use in connection with the drum head or closure;

Fig. 4 is a plan view of the blank forming the main portion of the drum head or closure;

Fig. 5 is a plan view of a paperboard disc adapted for use with the blank illustrated in Fig. 4;

Fig. 6 is a horizontal sectional view taken along line 6—6 in Fig. 1, looking in the direction of the arrows;

Fig. 7 is a vertical sectional view of a somewhat modified form of paperboard drum, illustrating the top closure element separated from the drum;

Fig. 8 is a plan view of a modified form of band for the closure;

Fig. 9 is a perspective view of the closure band element illustrated in Fig. 8, showing the ends of the band in assembled relation;

Fig. 10 is a plan view of a modified form of closure band element;

Fig. 11 is a perspective view of the closure band element illustrated in Fig. 10 showing the free ends of the band secured together;

Fig. 12 is a vertical sectional view of a still further modified form of drum which is adapted to be employed with any suitable form of closure element such as illustrated in Figs. 1 and 7, one of the band elements illustrated in Figs. 9 or 11 being employed to provide a reinforcing top edge for the drum;

Fig. 13 is a vertical sectional view of a still further modified form of drum showing the closure element separated from one end; and

Fig. 14 is a perspective view of the closure band element illustrated in Fig. 13 showing such band element in its condition prior to the step of folding its tabs around a reinforcing member such as a wire hoop.

The paperboard drum herein disclosed is intended to provide an exceptionally sturdy and rugged form of drum which will effectively replace drums of steel and heavy wooden barrels in the shipment of many types of plastic and liquid materials such as waxes, asphalt, resin and similar materials as well as many forms of powdered or comminuted substances.

Referring more particularly to the drawings, the paperboard drum, as illustrated in Fig. 1, comprises a cylindrical body member, indicated generally at 20, and upper and lower closure members, indicated generally at 21 and 22.

The body member 20 is shown in Fig. 2 in blank form and preferably comprises a rectangular sheet of strong paperboard or similar fibrous material having its ends brought together into overlapping relation and secured as by means of staples 23, 24 or other suitable securing means.

The upper and lower closure elements 21 and 22 of the paperboard drum illustrated in Fig. 1 are, in the present instance, identical and the description of one will therefore suffice. The closure 21 preferably comprises a main closure disc 24 and auxiliary disc 25 and a reinforcing band 26. The disc 24 is formed on its periphery with a securing portion in the form of a plurality of tab members 27, 27. These tab members are cut so as to form tapered notches therebetween so that the tabs will have parallel lateral edges, whereby they may be bent over so as to be disposed at right angles to the plane of the disc, in which position they will abut edge to edge.

For the purpose of facilitating bending over of the tabs 27, 27 the main closure disc 24 is formed with a substantially circular score or crease line 27a which is spaced inwardly a short distance from the inner termini of the tapered notches defining the tabs from each other. Short slits 27b, 27b are formed in the disc 24 between the score 27a and the ends of the notches. By this construction, the bending over of the tabs will be facilitated and edges of the tabs will be caused to lie in firm lateral engagement with each other to provide a tight closure construction.

While the tabs 27, 27 may be held in down-turned position in various ways, it is preferred

to employ the band element 26 having its ends secured together by a staple 28 or other suitable securing means, whereupon, the band is slipped over the disc 24 and into contact with the tabs 27 thereby holding the tabs firmly at right angles to the surface of disc 24. The tabs are preferably permanently secured to the band 26 as by means of staples 29, 29 clinched against the inner faces of the tabs.

The auxiliary disc 25 is intended to be secured centrally on the disc 24 and is so dimensioned as to provide an annular recess between the edge of the disc 25 and the down-turned tabs 27, 27. As shown in Fig. 1, this recess indicated at 30, is adapted to receive the end of the body member 20.

The disc 25 is suitably cut away at 31 so as to provide a slightly enlarged part in the annular recess 30, indicated at 32 so as to accommodate the extra thickness of the body member due to the overlapping of the ends of the body member. (See Fig. 6.)

As previously stated, the closure 22 is preferably identical in construction with the top closure 21, however this bottom closure is preferably permanently secured to the lower end of the body member 20 by means of staples 22a, 22a which pass through the tabs 27, the reinforcing band 26 and the body member 20 and are clinched against its inner surface.

Referring to Figs. 7 to 12 inclusive illustrating certain modifications of the form of drum just described, the drum therein illustrated comprises a body member, indicated generally at 35, and upper and lower closure members indicated generally at 36 and 37.

The body member 35 is formed from a rectangular sheet of paperboard similar to that shown in Fig. 2 and has its ends secured together as by means of staples 38, 38. The upper end of the body member 35 is provided with a reinforcing band 39 which may be similar to the band 26 shown in Fig. 3, or integral with member 35 and defined therefrom by a conventional cut score line. This band is secured to the outer surface of the body member 35 by securing means such as staples 40, 40.

The closure element 36 comprises a disc 42 similar to the disc 24 having tabs 43, 43 formed on its periphery which are adapted to be folded downwardly at right angles so that their side edges will abut as explained previously in connection with the closure disc 24.

For the purpose of holding the tabs 43, 43 in a position at right angles to the disc 42, there is provided a reinforcing band 44 having its ends secured together by staples 45, 45 and having along one edge a fold-over section or flange member 46 defined from the section 44 by means of a score or crease line 47 and in which is formed a plurality of closely spaced score or crease lines 48, 48 thereacross, giving the desired degree of flexibility to the fold-over flange member 46, whereby, after the ends of the band 44 have been secured together, the flange member 46 may be bent inwardly and then upwardly as viewed in Fig. 9 to form a band element that is U in shape in cross-section, as best seen in Fig. 7.

The band 44 is assembled with the folded-over tabs 43 by first placing the unscored part in contact with the outer surfaces of the tabs and then forcing the scored flange member 46 over and into flat contact with the inner faces of the tabs 43, 43, in which position the flange member 46 will contact the inner faces of the tabs with a degree

of firmness depending upon the thickness and strength of the material from which the band 44 is formed. When the band element 44 has been folded over the tabs 43 as just explained, the parts are preferably stapled as indicated at 49, 49.

The inner disc 50 is similar to the disc 25 except that in the present instance this disc is made somewhat smaller in diameter so as to accommodate the extra thickness of the upper edge of the drum as seen in Fig. 7. Thus, between the periphery of the disc 50 and the surface of the section 46 of the reinforcing band 44, there will be formed an annular recess 51.

The disc 50 will preferably be cut away at one portion, not shown, in a manner similar to the cut-away portion 31 of disc 25. (See Fig. 5.)

The construction of the lower end of the drum illustrated in Fig. 7 will now be described. It is to be noted that the lower end of the body member 35 is not provided with a band such as 39 secured to the top. The lower closure element 37 may be identical with the upper closure element 36 except that it is very slightly smaller in diameter due to the lessened thickness of the lower end of the body member. The reinforcing disc 50 will provide between its edge and the inner faces of the foldable section 46, an annular recess 51a into which the lower edge of the body member 35 is intended to fit rather snugly. This annular recess is shown slightly larger than it actually would be for the purpose of clarity. A sealing compound 51b is preferably introduced into the recess 51a so that it will effectively close the joint between the lower edge of the drum body 35 and the closure 37.

The closure element 37 is preferably permanently secured to the lower edge of the body member 35 by means of staples or similar securing means.

The reinforcing band 44 is suitably cut away as indicated at 52 in Fig. 8 so as to facilitate turning in the foldable section 46 at the stapled joint in the reinforcing band.

The modified form of reinforcing band illustrated in Figs. 10 and 11 comprises a strip 53 and a fold-over section or flange member 54, defined therefrom by a score or crease line 55. The flange member 54 is provided with a plurality of closely spaced score or crease lines 56, 56 thereacross to facilitate the folding of the flange 54 when the band has been secured in circular form.

The ends of the band 53, as illustrated in Fig. 11, are secured together as by means of staples 57, 57. Instead of forming a cut-out portion such as indicated at 52 in the band 44, the flange member 54 is separated from the main portion 53 by means of a notch 59 extending inwardly from the end substantially as far as the extent of the overlap to form an extension on the flange member. (See Fig. 11.) The extension on the flange member 54 is also preferably stapled to the other end of the flange member as indicated at 60, 60.

The band 53 is adapted to be assembled with the fold-over tabs 43 of the closure element in the same manner as described above in connection with the band 44.

The band 53 is also adapted for use in the construction of drum illustrated in Fig. 12. In this view, there is shown a body member 62 formed from a rectangular blank of sheet material similar to that illustrated in Fig. 2. The upper end of the body member 62 is provided with a reinforcing rim formed from the band 53 illustrated in Figs. 10 and 11. Staples 63, 63 are preferably

employed for securing the band 55 to the upper end of the body member 62.

The lower end of the body member 62 is provided with a closure which comprises a disc 64 having down-turned tabs 65, 65 adapted to lie snugly against the inner surfaces of the lower end of the body member 62. A band member 66 which is substantially identical with the band member 53 is secured on the lower end of the body member and has its unscored part on the outside, with the scored part on the inside of the drum, bearing against the tabs 65, 65 on the closure disc. The band member 66 is preferably so constructed as to provide a wider fold so as to accommodate at least two thicknesses of paper-board, namely, the tabs 65, 65 and the lower end of the body member 62. After the band member 66 is placed in proper position on the lower end of the body member, the fold-over section 67 is forced upwardly and then inwardly into contact with the tabs 66, after which the band member may be secured to the body member by means of staples 68, 68.

The modified form of drum illustrated in Figs. 13 and 14 will now be described. The drum disclosed in Fig. 13 comprises a body member 70 formed from a rectangular blank of sheet material and is provided with an upper closure member 71 and a lower closure member 72. The upper closure member 71 comprises a disc 73 having down-folded tabs 74, 74 on its periphery. These tabs are held in position by a closure band member 75 having a fold-over section 76 defined from the principal part of the band 75 by means of a score or crease line 77. The ends of the band are held together by means of staples 78 and one end of the band is cut away at the end of the fold-over section 76 as indicated at 79, making the band substantially identical with the band 44. The closure 73 has an auxiliary closure disc 80 secured to the under-side of the disc 73 as by means of adhesive. After the tabs 74, 74 have been folded to a position at right angles to the disc 73, the band 75 is adapted to be placed there-over. Before placing the band over the disc and in contact with the tabs, the fold-over section 76 is folded so as to lie in substantial contact with the part 75. A reinforcing member preferably in the form of a heavy wire loop or hoop 81 is enclosed between the fold-over section 76 and part 75 so as to give greatly increased strength to the closure. After the band is in place, as indicated in Fig. 13, the band is preferably secured to the tabs by means of staples 82, 82.

As previously described in the other forms of closure, the auxiliary disc 80 is so dimensioned as to leave an annular groove 83 between the down-turned tabs 74, 74 and the edge of the disc 80. This annular groove will thus accommodate the end of the body member 70 and make a snug closure.

The lower closure 72 is preferably identical with the upper closure 71 except that it is preferred to have this closure permanently secured to the lower end of the body member 70 and, for this purpose, staples 85, 85 are employed which pass through the body member as well as the tabs 74, 74 and the two thicknesses of the band member 75.

The annular recess or groove 83 provided by the bottom closure construction is arranged to receive the lower ends of the body member 70 to form a snug fitting arrangement.

From the foregoing it is to be observed that the construction of drum illustrated in the various modified forms provides a construction which is

simple in form but exceptionally sturdy and is adapted to withstand a considerable amount of hard usage in handling. While the present description sets forth certain preferred forms of the invention, numerous changes may be made in the construction without departing from the spirit of the invention and it is therefore desired that the present embodiments shall be considered in all respects as illustrative rather than restrictive, reference being had to the appended claims rather than to the foregoing description to indicate the scope of the invention.

I claim:

1. A drum of paperboard or similar sheet material comprising a body blank having oppositely disposed edge portions secured together in overlapping relation by staples or the like to form a substantially cylindrical body member, and a closure member for each end of said body member, at least one of said closure members including a closure disc having a plurality of tabs integrally formed on the periphery thereof, said tabs being at right angles to the plane of said disc and adapted to lie in non-overlapping relation around the outer surface of said body member at an end thereof, and a strip of said material having a longitudinal score line therein defining a band member and a flange member, said band member having its ends secured together by staples or the like and being in close contact with the outer surfaces of said tabs, and said flange member having a plurality of score lines thereacross and being folded over against the inner surfaces of said tabs, said tabs being secured at least to said band member by staples or the like.

2. A paperboard drum according to claim 1 including a second disc secured to the inner surface of said closure disc, said second disc having a diameter slightly smaller than the inside diameter of said body member at one end thereof, whereby said end lies between the periphery of said second disc and said flange member.

3. A paperboard closure for a substantially cylindrical drum comprising a closure disc having a plurality of tabs integrally formed on the periphery thereof, said tabs being at right angles to the plane of said disc and lying in adjacent non-overlapping relation, and a strip having a longitudinal score line therein defining a band member and a flange member, said band member having its ends secured together by staples or the like and lying against the outer surfaces of said tabs, and said flange member having a plurality of score lines thereacross and being folded over against the inner surfaces of said tabs, at least a major portion of said tabs being secured at least to said band member by staples or the like.

4. A closure according to claim 3 wherein said strip has a slot in one end in line with said longitudinal score line defining an extension on said band member and an extension on said flange member, both of said extensions overlapping and being secured to the opposite ends of their respective members.

5. A paperboard closure for a substantially cylindrical drum comprising a closure disc having a plurality of tabs integrally formed on the periphery thereof, said tabs being at right angles to the plane of said disc and lying in adjacent non-overlapping relation, and a strip having a longitudinal score line therein defining a band member and a flange member, said band member having its ends secured together and lying perpendicular to said disc exteriorly of said tabs, and said flange member having a plurality of score

lines thereacross and being folded over to lie against one of the surfaces of said tabs, at least a major portion of said tabs being secured at least to said band member by staples or the like.

6. A paperboard closure according to claim 5 wherein each of said tabs is secured at least to said band member and said flange member.

7. A paperboard closure according to claim 5 including a wire loop engaged between said band member and said flange member adjacent said 10 longitudinal score line.

8. A paperboard closure according to claim 5 including a wire loop engaged between said band member and said flange member adjacent said 15 longitudinal score line, said members being secured to the outer surface of each of said tabs.

9. A drum of paperboard or similar sheet material comprising a body blank having oppositely disposed edge portions secured together to form a substantially cylindrical body member, and a 20 closure member for at least one end of said body member including a closure disc having a plurality of tabs integrally formed on the periphery thereof, said tabs being at right angles to the plane of said disc and lying in adjacent non-overlapping relation, and a strip having a longitudinal score line therein defining a band member and a flange member, said band member having its ends secured together and lying perpendicular to said disc and exteriorly of said 25 tabs, and said flange member having a plurality of score lines thereacross and being folded over to lie against one of the surfaces of said tabs, at least a major portion of said tabs being secured at least to said band member by staples or the like.

10. A drum according to claim 9 wherein said staples also pass through and secure said flange member in folded position.

11. A drum according to claim 9 wherein said 5 staples also pass through said body member adjacent one end thereof.

12. A drum according to claim 9 wherein said flange member is folded over the ends of said tabs and one end of said body member, and said staples also pass through said flange member and 10 said body member.

13. A drum according to claim 9 including a second disc secured to the inner surface of said closure disc and so dimensioned as to provide an annular recess adjacent the periphery thereof adapted to receive one end of said body member.

14. A drum according to claim 9 including a second disc secured to the inner surface of said closure disc and so dimensioned as to provide an 20 annular recess adjacent the periphery thereof wherein one end of said body member is received, and a sealing compound filling the small openings between said body member and the means defining said recess.

15. A paperboard element adapted for use with 25 a substantially cylindrical paperboard drum comprising a strip having a longitudinal score line therein defining a band member and a flange member, said band member being adapted to have its ends secured together so as to form an annular structure, and said flange member having a plurality of score lines thereacross, whereby said flange member can be folded over to lie within and substantially coaxial with said band member.

RAYMOND H. VAN SAUN.
